UNITED STATES PATENT OFFICE.

MARTHA WENZEL, OF JACKSONVILLE, FLORIDA.

CIGAR AND CIGARETTE LIGHTER.

1,251,312.

Specification of Letters Patent. Patented Dec. 25, 1917.

Application filed January 3, 1917. Serial No. 140,413.

To all whom it may concern:

Be it known that I, MARTHA WENZEL, a citizen of the United States, residing at Jacksonville, in the county of Duval, State 5 of Florida, have invented certain new and useful Improvements in Cigar and Cigarette Lighters; and I do hereby declare the following to be a full, clear, and exact description of the invention, such as will enable others skilled in the art to which it appertains to make and use the same.

This invention is an improvement in electric igniting devices and has particular reference to a cigar and cigarette lighter.

15 An object of the invention is to provide a lighter wherein the current employed to produce an electric spark will only be used at the time of making the spark whereby the current consumption will be reduced to 20 a minimum and the life of the batteries prolonged.

Another object is the provision of a device of this character which is simple in construction, easy to manufacture, and effective 25 in carrying out the purpose for which it is designed.

The inventive idea involved is capable of receiving a variety of mechanical expressions, one of which, for the purpose of illustrating the invention, is shown in the accompanying drawing, wherein:

Figure 1 is a side elevation of the device constructed in accordance with the invention.

35 Fig. 2 is an end view thereof.

Fig. 3 is a fragmentary vertical section.

Fig. 4 is a section on the line 4—4 of Fig. 2.

Referring more particularly to the accompanying drawings in which like reference characters indicate similar parts, the numeral 5 indicates a casing in which are mounted the usual batteries, not shown, and on which is rotatably mounted in the brackets 6 a cylindrical reservoir 7 having the wick tube 8 extending therefrom and provided with an electric contact 9 at the upper end thereof suitably connected to the electric battery. The reservoir 7 is provided 45 with the usual handle or finger piece 10 for the purpose of oscillating the wick tube whereby the wick therein is lighted in a manner which will appear in the course of the description.

55 The casing 5 has mounted thereon a hollow standard 11 the upper end of which is

provided with a horizontal member 12. The lower extremity of this horizontal member has secured thereto in any preferred manner a hood member generally indicated by the 60 numeral 13 and consisting of a pair of depending and oppositely disposed plates 14 for receiving therebetween the upper end of the wick tube 8, said plates assisting in extinguishing the flame after the wick has 65 been lighted and returned to normal position. The upper portion 15 of the hood member has mounted therein the shank 16 of a bifurcated or forked element 17, said latter element being separated from the upper portion 15 by means of the insulation 18. The shank 16 forms a contact member which is adapted to be engaged by the reduced end 19 of a pivoted contact member 20 mounted upon a bolt 21 extending between the ends 70 of the bifurcated member 17. This pivoted contact member is insulated from the member 17 by the bushings 22 engaged in the openings in the member 17 and surrounding the bolt 21. Other insulating washers 23 are 75 mounted on the bolt 21 and engage the outer faces of the member 17. The pivoted contact member or plate 20 has secured thereto the ends of several strands of twisted steel wire 24 which combine to form a flexible 80 element normally projecting into the space between the plates 14 of the hood member 13. The ends of these wires which are secured in the member 20 are preferably wound with asbestos thread 25 to prevent the heat 85 from destroying said wires. An electric wire 26 leads from one pole of the source of current in the casing 5 up through the standard 11 and is connected to the shank 16, while the other pole of said source of current is 90 connected to the contact 9 through one of the brackets 6, reservoir 7 and tube 8. In practice, when the wick tube is in its normal position between the plate 14 and it is desired to light the wick therein, the handle 10 is 95 depressed which causes the wick tube to move outwardly from between the plate 14 and the contact 9 on said tube will then engage the free ends of the wires 24. This engagement will also cause said wires to move 100 outwardly and adjust the pivoted contact member 20 about its pivot until the reduced end 19 thereof engages the adjacent end of the shank 16. The circuit is closed by this latter engagement and the spring contact 105 formed by the wires 24 is so positioned relative to the contact 9, carried by the wick 110

tube, that when these terminals are separated by the continued outward movement of the wick tube, a spark will occur the instant of separation and said spark will light the wick 5 in said tube, it being understood of course that said wick is saturated with a suitable fluid from the reservoir 7. It will thus be seen that the current is only used during the time intervening between the contact of the 10 end 19 with the shank 13 and the instant of separation between the spring contact 24 and the contact 9. When the wick tube 8 is being returned to its normal position the same will engage the spring contact or wires 25 15 and thus rock the pivoted contact 20 until the end 19 is disengaged from the shank 13 and owing to the flexibility of the spring contact 24 the tube 8 is permitted to return to its normal position when the device 20 will be ready for another operation.

What is claimed is:—

1. In a device of the class described, the combination with a casing having a source of current therein, of a wick tube mounted 25 to oscillate above said casing and having a contact, a hood device also supported above said casing and including oppositely disposed plates for receiving the upper end of said wick tube therebetween when the latter 30 is in normal position, a bifurcated member carried by said hood device and connected

to said source of current, another contact pivoted between the arms of said bifurcated member and insulated therefrom and a spring contact carried by said pivoted contact and adapted to be engaged by the upper end of said wick tube whereby to cause said pivoted contact to engage said bifurcated member and said spring contact to engage the contact on said wick tube. 40

2. In a device of the class described, the combination of a casing having a source of current therein, of an adjustable wick tube carried by said casing and having a contact, a hood device also supported by said casing, a bifurcated member carried by said hood device and connected to said source of current, another contact pivoted between the arms of said bifurcated member and insulated therefrom, and a spring contact carried by said pivoted contact and adapted to be engaged by the upper end of said wick tube whereby to cause said pivot contact to engage said bifurcated member and said spring contact to engage the contact on said wick tube. 45

In testimony whereof, I affix my signature, in the presence of two witnesses.

MARTHA WENZEL.
